UNITED STATES PATENT OFFICE.

NATHANIEL J. CUSHMAN, OF NORTH PARIS, MAINE.

SAW-MILL DOG.

SPECIFICATION forming part of Letters Patent No. 340,491, dated April 20, 1886.

Application filed February 3, 1886. Serial No. 190,723. (No model.)

To all whom it may concern:

Be it known that I, NATHANIEL JOHNSON CUSHMAN, of North Paris, in the county of Oxford and State of Maine, have invented a new and useful Improvement in Frost-Dogs, of which the following is a specification, reference being had to the annexed drawings, forming a part thereof, in which—

Figure 1 is a side elevation of my improved frost-dog. Fig. 2 is a front elevation. Fig. 3 is an inverted plan view of the arm of the dog. Fig. 4 is a plan view of the standard.

Similar letters of reference indicate corresponding parts in the different figures of the drawings.

The object of my invention is to provide for the carriages of saw-mills a dog for clamping green frozen logs upon the saw-mill carriage while being sawed into boards, plank, or joists.

My invention consists in the construction and arrangement of parts, as will be hereinafter fully described and claimed.

The base A, which is designed to be secured to the log-beam of a saw-mill carriage, supports two vertical round standards, B C, which are parallel with each other, the standard B being shorter than the standard C. An arm, D, provided with three or more apertures, a, and having around the series of apertures a flange, b, is received upon the standards B C, the standards B C entering two of the adjacent holes a, and serving to support the arm in a horizontal position while allowing it to move vertically, but not laterally.

To the under surface of the arm D, at opposite ends, are secured steel points c, which engage the lumber to be held in place by the frost-dog. For convenience in handling, opposite sides of the arm D are provided with handles d, which project outward laterally beyond the edges of the flange b, and in opposite edges of the flange b are formed semi-

circular recesses e, for receiving the end of the shorter standard, B, when the arm is raised above the end of the standard B and turns 45 through a quarter of a revolution, as shown in Fig. 2. By this means the arm D, when not in use, is prevented from turning or falling by the engagement of the shorter standard, B.

The length of the arm D may be adjusted with reference to the lumber carried by the mill-carriage by shifting the standards B C in the holes a, or by reversing the arm on the longer standard, C.

One or more of these dogs may be employed upon a single mill-carriage, and when allowed to rest by their own gravity with their points c entering the lumber on the carriage the lumber will be held firmly while being edged 60 or slit up into strips.

Having thus described my invention, what I claim as new, and desire to secure by Letters Patent, is—

1. The combination, with the base-plate A 65 and standards B C, of different lengths, of the arm D, provided with the points c, having apertures a, for receiving the standards B C, and provided with recesses e, for engagement with the end of the shorter standard, B, substantially as herein shown and described.

2. The combination, in a saw-mill dog, with the base having the vertical standards, of the transverse arm having a greater number of vertical apertures than there are standards, 75 through which apertures the standards may pass to allow the arm to be adjusted, and log-engaging teeth depending from opposite ends of the said arm, substantially as set forth.

NATHANIEL J. CUSHMAN.
